UNITED STATES PATENT OFFICE.

THOMAS LEE, OF CINCINNATI, OHIO.

PEANUT-ROASTER.

SPECIFICATION forming part of Letters Patent No. 320,804, dated June 23, 1885.

Application filed June 2, 1884. (No model.)

To all whom it may concern:

Be it known that I, THOMAS LEE, of Cincinnati, in the county of Hamilton and State of Ohio, have invented a new and useful Improvement in Peanut-Roasters, which improvement is fully set forth in the following specification and accompanying drawings, in which—

Figure 1 is a perspective view of my improved peanut-roaster. Fig. 2 is a perspective view of the same with the cylinder in position, and Fig. 3 plan view of Fig. 1.

In the peanut-roasters in general use considerable annoyance is experienced in charging and discharging the contents from the cylinder in roasting. I design to overcome this difficulty in the present device by constructing a roaster having a cylinder journaled to a horizontal frame, so arranged as to slide inwardly and outwardly at the side of the machine, by means of which the said cylinder may be drawn out partially and returned to its original position within the roaster when filled. The journal at the outer end is formed hollow and contains therein a sampler, all of which will now be fully set forth in detail.

In the accompanying drawings, A is a frame of ordinary construction. At one of the ends I provide a chute and lid, B, by means of which fuel may be put into the interior. Immediately beneath the chute an opening, C, is provided, having a vertical sliding plate, D, through which the ashes and cinders may be removed. The opposite end is also provided with a similar opening and plate, by means of which the cinders may be removed from that side. A perforated plate extends from the bottom of chute B. This plate is depressed in the center, and a portion, E, extends diagonally upward to the base of the chute, while the opposite portion G extends diagonally in the opposite direction. This perforated plate accommodates and supports the coal or other combustible material and forms an ideally perfect grate.

Within one side of the frame of the roaster I provide a rectangular frame, H, sliding on ways I, secured to the inner sides of the ends

of the roaster. Journaled within this rectangular frame I provide an ordinary cylinder, J. The opening in the side of the roaster is designed to be of such a size as to receive therein the cylinder and frame, so as not to permit the heat to escape therefrom through the same. The journal K of the roaster is designed to be tubular in form, to receive thereon the crank L, for revolving the same, while within the tubular opening a sampler, M, is placed, by means of which latter the process of roasting the peanuts may be tested at its various stages. I design to provide sliding plates N on opposite sides of the outer end of the cylinder in place of a single opening, as heretofore.

In operating my device the cylinder and frame are pulled outwardly from the roaster, the cylinder is then charged and, with the rectangular frame, returned to its original position. The process of roasting is then gone through with, after which the cylinder and frame are again pulled outwardly and the nuts removed.

It will be observed by reference to Fig. 3 that the cylinder J is constructed with an annular flange, a, on its outer end and an annular flange, a', on its inner end. These flanges are designed to close the joint between the case A and cylinder J when the latter is fully drawn out and when it is closed.

It will also be observed that the two inclined perforated plates E G constitute a grate which is especially applicable to the cylinder J, for the reason that the bed of incandescent coal is brought in close relation to this cylinder, and free access of air is permitted below said plates through openings C.

It will furthermore be observed that I provide an inclined chute or feeder, which extends beyond the wall of the case A, and facilitates the introduction of fuel.

What I claim is—

1. In a roasting apparatus, the combination of a case, A, a roasting-cylinder, and a sliding frame which carries the same, and a grate below the cylinder composed of an angular perforated plate, E G, secured to the case A, substantially as set forth.

2. In a roasting apparatus, the combination of a case, as A, a cylinder, and a sliding frame which carries the same, a grate below the cylinder, composed of an angular plate, E G, 5 secured to the case, and a feeding-chute in the side of the case for the introduction of fuel, and a hinged cover for said chute, substantially as shown and described.

In testimony that I claim the foregoing I have hereunto set my hand this 26th day of 10 May, 1884, in the presence of witnesses.

THOMAS LEE.

Witnesses:

HENRY J. HARROP,
WALTER ALCOKE.
